UNITED STATES PATENT OFFICE

WILLIAM A. READY, OF BROOKLINE, MASSACHUSETTS

METHOD OF MAKING D-HANDLES FOR SHOVELS AND THE LIKE

Original application filed September 4, 1930, Serial No. 479,665. Divided and this application filed March 9, 1931. Serial No. 521,180.

My invention aims to provide improvements in the method of making D-handles and assembling the parts of D-handle casing.

This application is a division of my co-pending application Serial No. 479,665, filed September 4, 1930.

In the drawings, which illustrate a preferred embodiment of my invention:—

Figure 1 is an elevation view of my invention showing the upper end of a split stave incased in a sheet metal casing;

Fig. 2 is a view of the sheet metal casing before attachment to a stave, the lower portion being in cross-section to show the means which holds the parts of the casing in assembled relation;

Fig. 3 is a part section and part elevation of a portion of the casing showing the method of assembly of the two parts;

Fig. 4 is a view of the parts shown in Fig. 3 after they have been completely assembled; and

Fig. 5 is a section taken on the line 5—5 of Fig. 4.

With reference to the drawings, I have shown a D-handle which includes a casing 1 preferably formed from sheet metal and combined with the split end of a stave 2 and a grip piece 3, as shown in Fig. 1. The general construction of the handle, except for the means by which the casing parts are secured together, and the method of assembly of the three parts of the handle is substantially the same as shown and more fully described in my co-pending application Serial No. 341,181, filed February 19, 1929. Since my present invention relates to improvements in the casing and the method of assembling the parts thereof, it will not be necessary to describe in detail the general construction of the handle and the method of assembly.

My improved casing 1 is formed from two identical hollow sheet metal parts, each of which is semi-cylindrical in cross-section and has a flat face provided by inwardly bent flanges 4, 4, as shown in Figs. 4 and 5. Each part also has a vertical flange 5 adjacent to the stave-receiving end and a hook shaped portion 6 extending from one end of a flange

4, as best shown in Fig. 2.

When the parts of the casing 1 are secured together, as shown in Fig. 2, the flange 5 of one part underlies a portion of another part (Fig. 5), and is welded thereto to secure the parts together. Also, the hook portions 6 under the terminal edges of flange portions 4 (Fig. 2), so that when the side arms of the casing are bent into Y-shaped formation the casing will not spread beyond the hook portions and therefore the stave will not be split.

While the handle construction shown and described in my co-pending application referred to above is satisfactory for general purposes, it has been found that the casing parts will pull apart where they are joined together when placed under heavy strain such as when the handle is used for a "pry". Therefore I have overcome this objection by the construction used in my present form of device because, when the wooden arms of the stave are forced into the hollow arms of the casing 1, the hook portions are held tightly against the flanges 4 and provide, with the welded portions, a strong durable connection to prevent separation of the casing and splitting of the stave beyond that point.

The method of assembling the parts of the casing is, I believe, unique because the construction is such that the parts can be assembled only by placing them together with their flat faces in engagement and with the longitudinal axis of one part angled relative to the longitudinal axis of the other, as shown in Fig. 3. This is necessary because of the opposed hooks which can be engaged beneath the flanges 4 only in this manner and thereafter rotating one part relative to the other to bring them into the positions shown in Figs. 2 and 4. By this method of assembly, all of the elements may be preformed and then the casing may be welded along the lines of the underlying flanges 5 (Fig. 5) to secure the parts together and thus form a strong durable casing, as shown in Fig. 2. The hook portions are offset from the center (5) of each casing part so as not to interfere with each other and to facilitate assembly as well as to provide a strong assembly across the entire width of the casing.

When the parts are assembled by the

method just described they are securely fixed together at one end and the outer surface is smooth and presents a neat appearance.

While I have illustrated and described a preferred embodiment of my invention, I do not wish to be limited thereto because the scope of my invention is best defined by the following claims, some of which are intended to be of such scope as to cover other variations.

10 Claims:

1. The method of making a D-handle having a metal casing formed in two hollow parts having means adjacent to one end adapted to 15 be interlocked which comprises securing the parts together by approaching them face to face toward each other with the axis of one at an angle to the other and then turning the parts relative to each other to bring their 20 axes in alignment and lock the casing parts together by engagement of the interlocking means and thereafter attaching the casing to the split end of a stale.

2. The method of making a D-handle having a metal casing formed in two hollow parts having means adjacent to one end adapted to 25 be interlocked which comprises securing the parts together by approaching them face to face toward each other with the axis of one at an angle to the other and then turning the parts relative to each other to bring their 30 axes in alignment and lock the casing parts together by engagement of the interlocking means, splitting the end of a stale to provide 35 a pair of connecting portions, securing the stem to the casing by longitudinal approaching movement thereby forcing the connecting portions of the stale into the hollow parts of the casing, bending the casing parts and connecting portions of the stale together into 40 substantially a Y-shaped formation and then securing a grip between the open ends of the Y-shaped formation.

3. The method of assembling the parts of 45 a metal D-handle casing having two parts each of which, adjacent to the stale-receiving end, has a vertical flange and a hook-like portion and a flat face, the hook-like portion extending from the flat inner face at one side 50 of the center thereof which comprises approaching one of said parts toward the other with one flat face toward the other and with one part having its longitudinal axis at an angle to the longitudinal axis of the other thereby to permit the hook-like portions to 55 pass beneath the edges of the flat faces and thereafter to turn the two parts to bring their axes into alignment and engage the hook-like portions beneath the edges of the flat faces.

4. The method of assembling the parts of a metal D-handle casing having two parts each of which, adjacent to the stale-receiving end, has a hook-like portion and a flat 60 face, the hook-like portion extending from the flat inner face at one side of the center

thereof which comprises approaching one of said parts toward the other with one flat face toward the other and with one part having its longitudinal axis at an angle to the longitudinal axis of the other thereby to permit the hook-like portions to pass beneath the edges of the flat faces and thereafter to turn the two parts to bring their axes into alignment and engage the hook-like portions beneath the edges of the flat faces.

5. The method of assembling the parts of a metal D-handle casing having two parts each of which, adjacent to the stale-receiving end, has a vertical flange and a hook-like portion and a flat face, the hook-like portion extending from the flat inner face at one side of the center thereof which comprises approaching one of said parts toward the other with one flat face toward the other and with one part having its longitudinal axis at an angle to the longitudinal axis of the other thereby to permit the hook-like portions to pass beneath the edges of the flat faces and thereafter to turn the two parts to bring their axes into alignment and engage the hook-like portions beneath the edges of the flat faces and the vertical flanges over the edges of the cooperating parts and then welding the two parts together at the overlapped vertical flanges.

In testimony whereof, I have signed my name to this specification.
